UNITED STATES PATENT OFFICE.

CARLOS M. DEL VALLE, OF NEW YORK, N. Y.

TRousERS STRETCHER.

Application filed September 17, 1927. Serial No. 220,168.

This invention relates to a trousers stretcher.

The object of the invention is the production of a trousers stretcher which can be easily attached to the legs of a pair of trousers and maintain the creases therein. The second object of the invention is the production of a trousers stretcher the length of which can be easily varied. The third object of the invention is the production of a trousers stretcher which will maintain the creases in a pair of trousers without any injury thereto. The fourth object of the invention is the production of a trousers stretcher adapted to engage the creases of the legs of a pair of trousers when worn, and which will also engage said creases when not worn.

In the accompanying drawings Fig. 1 represents a plan view of an exemplification of the adjustable trousers stretcher; Fig. 2 shows a right hand side view of a fragmentary portion of Fig. 1; Fig. 3 is an enlarged fragmentary portion of Fig. 1; Fig. 4 represents a front view of Fig. 3; Fig. 5 is a section of Fig. 4 on the line 5, 5; Fig. 6 indicates an enlarged partial top view and section of Fig. 2 on the line 6, 6; Fig. 7 shows a section of a leg of a pair of trousers and partial side view and section of Fig. 1 on the line 7, 7, and Fig. 8 shows a plan view of a modification of the trousers stretcher.

The trousers stretcher preferably comprises a pair of flexible bowed bands, which each comprise an inner resilient main band 20, which has formed therein a plurality of locking openings 21, and has extending therefrom a plurality of guide pins 22. A pair of outer resilient bands 28 are in slid-able engagement with, and oppositely positioned upon the outer faces of each of the inner resilient main bands 20. Each of the bands 28 has formed therewith a spring locking latch 29, which is adapted to lock with its adjacent locking openings 21. The latches 29 are made by cutting small strips in the bands 28, and then pressing the strips to make them of the proper length before bending them. Guide openings 30 are formed in each of the bands 28 and they each engage the body portion of one of the guide pins 22, and maintain the bands 28 in slid-able relation to the band 20. By engag-ing the spring locking latch 29 in the dif-ferent openings 21, the members 28 can be

spaced different distances apart to vary the distance between the outer ends of the bowed bands. At the outer end of each band 28 is formed a return bend 31, which form a practically cylindrical seat 33, the extreme end of which is welded to or otherwise fastened to the main portion of said band as indicated at 34. The outer end of each band 28 is pyramidal in shape as indicated at 35, and has formed therewith the curved nose 36. A latch opening 39 is made in each return bend 31, and the material cut out is formed into a spring latch 40. The portion forming the spring latch 40 may be some-what flattened to reduce its thickness and thereby provide sufficient length of material to form the said spring latch. The said spring latches are adapted to engage the openings 39. An adjustable supplemental band 45 is provided for the outer end of each of the bands 28, and has formed there-with at one end the disc 46. The plane of the said disc 46 is at right angle to the body portion of its band 45, and an opening 47 is formed in each disc. At the other end of the band 45, there is formed a return bend 48 having the rounded nose 49. A barrel 50 extends from and below each disc 46 and rotatively engages the seat 33. The barrel 50 has formed therein a pair of seats 51 and 52 with their planes inclined to each other, and the spring latch 40 is adapted to engage each of said seats. A bolt 53 extends through the opening 47 and through an opening coaxial therewith in the barrel 50. A washer 54 encircles the bolt 53 and is maintained against the bottom face of the return bend 31, by means of the nut 55 which is in threaded engagement with the bolt 53. By means of the said bolt, washer and nut the barrel 50 is maintained in opera-tive position.

The supplemental bands 45 are normally maintained in their angular position rela-tively to the members 28 as indicated in full lines in the drawings; when the trousers stretcher is in position in the legs of a pair of trousers. In this position the spring latch 40 engages the seat 51 of the barrel 50. Each of the bands 45 may be turned to the position indicated in dotted lines in Fig. 1 with the body portion of each practically parallel to the plane passing through the axial centers of the barrels 50. With this latter location of the bands 45 the length of the bowed bands of the trousers stretchers

is increased. In this position of the bands 45, the seats 52 engages the spring latches 40.

The pair of flexible bowed bands are connected to each other by means of the vertical resilient bands 61, 62 and 63. The bands 61 and 62 have their ends welded or otherwise connected to the bands 28, adjacent to the outer ends of the latter, and the band 63 is connected to the central portion of each 10 of the main bands 20. The band 63 extends somewhat beyond the outer edge of one of the bands 20 and has an opening 64. Openings 65 may extend through the junction of each of the main bands 20 and the band 63.

15 Referring particularly to Fig. 7 a trousers leg is indicated at 70 with the trousers stretcher connected thereto. Pieces of fabric 71 or other suitable material have their ends stitched to the inner face of the leg of the 20 trousers and form loops which engage and support the bands 28, and similar pieces of fabric 72 have their ends stitched to the inner face of the trousers and form loops which engage and support the bands 20. Each of 25 the bands 20 and the ends of the bands 63 may be stitched to the legs of the trousers by threads engaging the openings 65.

It is to be understood that the flexible bowed bands of the stretchers when inserted 30 in the trousers will take about the shape indicated in Fig. 1 of the drawings, the noses 36 engaging the creases thereof and the resiliency of the bands 61, 62 and 63 maintain the lower portion of the trousers taut. 35 The lower flexible bowed bands are preferably attached to each trousers leg adjacent to its lower end and the upper resilient bowed bands are preferably located below the knee of the wearer.

40 It will be understood that before the bowed bands are inserted in the legs of the trousers that they are appreciably more flattened than indicated in Fig. 2 so that their resiliency when in place will engage the creases of the legs of the trousers, to maintain them creased.

When the trousers are hung up when not in use the supplemental bands 45 are locked in their outward position as indicated in 50 dotted lines in Fig. 1, and thereby the noses 49 engage the creases of the legs of the trousers and the latter are automatically pressed. The trousers can be hung by engaging a hook or other device with the openings 64 in the bands 63.

55 If desired the bands of the stretchers may be covered with a fabric indicated at 75. Spring steel may be used for the bands of the stretchers, although whale bone or other 60 suitable material may be used. The invention may also be used with only one of the bowed bands with its resilient bands 20 and 28, by connecting the same to the lower portion of each leg of the trousers, omitting 65 the upper bowed band and the connecting

bands. Both the latches 29 and 40 may be made by making the necessary openings therefor in their respective bands and return bends and welding or otherwise fastening the latches to said bands and return bends 70 for said openings.

Referring to Fig. 8 which indicates a modification of the trousers stretcher, the bowed band comprises a single resilient band 80 having the pyramidal ends 81 similar to 75 35. The said pyramidal ends have connected thereto the supplemental bands 45, each with its disc 46 and rounded nose 49.

Various modifications may be made in the invention and the present exemplification is 80 to be taken as illustrative and not limitative thereof.

Having described my invention what I desire to secure by Letters Patent and claim is:

85

1. In a trousers stretcher the combination of a resilient bowed band, comprising an inner resilient main band, a pair of outer resilient bands slidably connected to the main band, each of the outer bands having a curved nose at its outer end and means to lock the outer bands to the inner band in different positions.

2. In a trousers stretcher the combination of a resilient bowed band, comprising an inner resilient main band, a pair of outer resilient bands slidably guided and connected to the main band, each of the outer bands having a pyramidal outer end with a curved nose and means to lock the outer bands to the main inner band in different 100 positions.

3. In a trousers stretcher the combination of a resilient bowed band, a supplemental band pivoted to each end of the bowed band and a locking connection between the bowed band and each of the supplemental bands to lock the latter in different angular positions.

4. In a trousers stretcher the combination of a bowed band, comprising an inner resilient main band, a pair of outer resilient bands slidably guided and detachably connected to the main band, each of the outer bands having a pyramidal outer end with a curved nose and a practically cylindrical seat, a supplemental band for each of said outer bands, a barrel extending from each supplemental band engaging one of said seats and a locking device interposed between each barrel and its seat to lock said supplemental bands in different positions.

5. In a trousers stretcher the combination of a bowed band, comprising an inner resilient main band, a pair of outer resilient bands slidably guided and detachably locked to the main band, each of the outer bands having a return bend at its outer end forming a pyramidal outer end with a cylindrical seat, a spring latch formed with each return bend, a supplemental band for each pyram- 130

idal end, a barrel extending from each supplemental band having a pair of seats adapted to lock with said spring latch and means to maintain each barrel in operative position in its seat.

6. In a trousers stretcher the combination of a pair of bowed bands spaced from each other, a supplemental band pivoted to the ends of each of the bowed bands, means to

lock the supplemental bands in different angular positions, other bands at right angles to the bowed bands with the end portions of the latter connected to the bowed bands and means to connect the bowed bands to the legs of a pair of trousers.

15

In testimony whereof I affix my signature.

CARLOS M. DEL VALLE, M. D.
